(57) **CLAIM**

The ornamental design for an inoculator marker, as shown and described.

DESCRIPTION

FIG. 1 is a perspective view of an inoculator marker showing the design of the invention.

FIG. 2 is a side view thereof.

FIG. 3 is an end view thereof.

FIG. 4 is a top view thereof.

FIG. 5 is an opposite side view thereof.

FIG. 6 is an opposite end view thereof; and,

FIG. 7 is a bottom view thereof.

The broken lines shown in FIGS. 1-2 and FIGS. 4-7 illustrate portions of the inoculator marker and form no part of the claimed design.
